To all whom it may concern:

Be it known that I, JOSEPH E. STRAKER, Jr., a citizen of the United States, residing in Attleboro, in the county of Bristol and State of Massachusetts, have invented a new, original, and ornamental Design for the Handle of a Spoon or Similar Article, of which the following is a specification, reference being had to the accompanying drawings, forming part thereof and showing my design as embodied in the handle of a spoon.

Figure 1 of the drawings is a view of the obverse side of a spoon the handle of which illustrates the front view of my design in re-

lief, and Fig. 2 is a view of the reverse side 15 of a spoon the handle of which shows the same design as seen from the rear.

What I claim as new, and desire to secure by Letters Patent, is—
